[57] CLAIM

The ornamental design for a finger ring.

DESCRIPTION

FIG. 1 is a perspective view of a finger ring showing my new design;

FIG. 2 is a perspective view of a finger ring showing a second embodiment of my new design;

FIG. 3 is a perspective view of a finger ring showing a third embodiment of my new design, it being understood that the design is axially symmetrical; and,

FIG. 4 is a perspective view of a finger ring showing a fourth embodiment of my new design.

It being understood that FIGS. 1, 2, and 4 are symmetrical about an axis.
